US00D550174S

(12) **United States Design Patent** (10) Patent No.: **US D550,174 S**
(45) Date of Patent: **** Sep. 4, 2007**

(54) **IMAGE VIEWER**

(75) Inventor: **Michio Deguchi**, Tokyo (JP)

(73) Assignee: **Sony Corporation**, Tokyo (JP)

(**) Term: **14 Years**

(21) Appl. No.: **29/241,987**

(22) Filed: **Nov. 4, 2005**

(51) LOC (8) Cl. **14-03**

(52) U.S. Cl. **D14/126**

(58) **Field of Classification Search** D14/125-134,
D14/239, 371, 136, 374-377; 312/7.2; 348/836,
